BATHTUB AIR VENT

Buford F. Mondale, St. Paul, Minn.

Application March 28, 1955, Serial No. 497,039

2 Claims. (Cl. 4—179)

This invention relates to heating vents and more specifically relates to apparatus for discharging heating air into a bathroom.

Bathrooms in modern small houses are generally quite small and crowded and the amount of wall space adjacent the floor is at a minimum. It is oftentimes difficult to build in heating ducts or other sources of heat into bathroom walls because the various fixtures occupy a substantial portion of the wall area and because the water and drain pipes occupy much of the space between the walls. This is especially so in the bathroom walls adjacent the sink and toilet bowl. To get away from the water and drain pipes, air duct openings have frequently been built into the bathroom walls at approximately eye level which is quite objectionable to at least many people. One of the largest uninterrupted expanses of wall area in a bathroom is that which extends along the inner side of the bathtub. Although certain types of bathtubs have been developed in the past for discharging heat from beneath the tub or from the outer wall thereof, such bathtubs have had distinct disadvantages. One of the most important disadvantages is that the bathtub construction is made substantially more complicated by putting heating vents of the commonly known type into the outer apron wall.

Therefore it is to the substantial elimination of these and other disadvantages that my invention is directed, along with the inclusion therein of other novel features.

An object of my invention is to provide a bathtub construction which is adapted to cooperate with the room and wall surfaces to provide a heating air duct for discharging air through the bathtub apron side wall.

A further object of my invention is the provision of a novel vent in a bathtub apron side wall which is of simple and inexpensive construction and which will permit air to be discharged through the bathtub apron side wall without permitting water from the room to enter the chamber beneath the tub.

Still another object of my invention is the provision of a bathtub construction to form a plenum chamber beneath the tub and to provide further discharge of heating air from the plenum chamber downwardly toward the bathroom floor and over a large area of the floor.

These and other objects and advantages of my invention will more fully appear from the following description made in connection with the accompanying drawings wherein like reference characters refer to the same or similar parts throughout the several views and in which:

Fig. 1 is a cross section view taken on a vertical plane through a building construction and showing the bathtub including my invention in side elevation and partly broken away;

Fig. 2 is a section view taken on a vertical plane substantially at 2—2 of Fig. 1; and

Fig. 3 is a detail section view similar to a portion of Fig. 2 and showing a modified form of my invention.

The building construction is provided with suitably supported floor and wall surfacings 10 and 11 respectively

2

and a heating air duct 12 which opens through wall 11 adjacent the juncture between wall 11 and floor 10. Of course the heat duct 12 will be connected to a suitable source of hot air such as a furnace for supplying heating air to the bathroom. The bathtub construction which is indicated in general by numeral 13 includes substantially upright inner side walls 14, end walls 15 and a bottom 16, all of which are sealingly connected together and may be formed integrally of a continuous sheet of rigid material such as steel. An outwardly extending flange portion 17 may be formed integrally of the inner side walls 14 and extends around the entire periphery of the tub rim. Outer apron walls 18 extend downwardly from the flange portion 17 to the floor and may provide structural support for the tub. Depending upon the nature of the installation of the bathtub, an apron wall may be provided only at one side of the tub or may be provided at one end of the tub in addition to the side apron wall. In the form shown, apron wall is provided along one longitudinal side of the tub and across one end thereof. The bottom edges of the apron walls 18 and the outer edges of flange 17 which engage the wall surfacing are all sealingly connected to the respective surfaces so as to make the joint between the tub walls and the room surfacings water tight. The bottom 16 of the tub is supported in spaced relation above the room floor 10. The tub walls and bottom and the room wall and floor surfaces cooperate to define an air plenum chamber beneath the tub which communicates with the source of heating air, such as duct 12.

An elongated slot opening 19 is formed in the outer apron wall 18 and extends substantially horizontally. Slot 19 could as well be formed in the apron wall which extends across the end of the tub or an additional opening similar to 19 may be formed in the end apron wall 18. A baffle or deflector plate 20 is attached to the apron side wall adjacent the lower edge of opening 19 therein, and deflector plate 20 extends upwardly and inwardly of the chamber. Deflector plate 20 is, in the form shown, formed integrally of the outer apron wall 18 and may be formed by a stamping operation in the construction of the tub, or in cast iron tub construction, this can be a part of the original casting.

In the modification shown in Fig. 3, the apron side wall 25 is provided with an opening 26 at the bottom edge thereof and the deflector plate 27 is again mounted at the bottom edge of the opening 26 to extend upwardly and inwardly into the chamber 28 beneath the tub. In this form of the invention the apron side wall may be mounted directly on the floor or may be mounted on a block or rail 29. Deflector plate 27 may be formed integrally of the apron side wall, being connected thereto at its ends or may be mounted on the rail 29. In this form of the invention the baffle plate 27 may be constructed to swing into the plane of the apron side wall 25 to close the vent opening 26.

In operation, heating air will be delivered through the air duct 12 into the plenum chamber beneath the tub. Air will thereupon be discharged in a generally downward direction outwardly through the vent opening 18 as shown by arrows A. Even though there may be considerable splashing when the bathtub is used, especially as by children, so as to cause water to drain down the outside of the apron side wall 18, the deflector plate 20 will restrict entrance of water into the plenum chamber beneath the tub. This is especially true where a shower head is incorporated with the bathtub fixtures because oftentimes the shower curtain is left hanging on the outside of the tub apron wall and will cause water to drain down the outer side of the tub.

It should be seen that I have provided a new and improved bathtub construction for permitting heating air

to be discharged through the tub apron side wall in a generally downward direction to thoroughly heat the floor area of the bathroom and in a manner that water is restricted from entering the plenum chamber beneath the tub.

It will, of course, be understood that various changes may be made in the form, detail, arrangement and proportion of the parts without departing from the scope of my invention which consists of the matter described therein and set forth in the appended claims.

What is claimed is:

1. A bath tub construction for use in a building room having room-defining floor and wall surfaces, comprising a bathtub sealed to the room-defining surfaces and having sealingly interconnected inner tub walls, a bottom and at least one apron wall depending from the rim of the tub to the floor, said bottom being spaced off the floor and cooperating with said walls to define a plenum chamber communicating with an air duct in one of the room-defining surfaces, said apron wall having a slot opening therein for discharging air from the plenum chamber into the room, said slot opening having upper and lower edges, an inclined deflector plate formed integrally of said apron wall and extending upwardly from said lower edge into said chamber, said plate being arranged for restricting water running down the apron wall from entering said plenum chamber, whereby heating air will circulate

through said chamber and out the opening in said apron wall.

2. An air vent construction for use in a bathroom having floor and wall surfaces and a heating duct discharging air through one of the same adjacent the juncture between the floor and wall, comprising a bathtub having integral upright inner walls and a bottom and at least one outer apron wall, said walls having edges adapted for sealed connection to such room-defining surfaces to define a plenum chamber between said tub and such room-defining surfaces, said plenum chamber communicating with such an air duct, said apron wall having an elongated and generally horizontally extending opening therein for discharging heating air therethrough, said opening having a lower portion, and an inclined deflector plate connected with said apron wall adjacent the lower portion of said opening and extending upwardly and inwardly of the chamber to preclude water running down the side of the tub from entering said chamber, whereby heating air discharged through said opening will be directed toward the floor of the room.
